UNITED STATES PATENT OFFICE.

MARION MALLORY AND LUTHER EARL SEVISON, OF TOLEDO, OHIO.

IGNITION SYSTEM FOR INTERNAL-COMBUSTION ENGINES.

Application filed April 26, 1923. Serial No. 634,735.

To all whom it may concern:

Be it known that we, MARION MALLORY and LUTHER EARL SEVISON, citizens of the United States, and residents of Toledo, in the county of Lucas and State of Ohio, have made an Invention Appertaining to an Ignition System for Internal-Combustion Engines, which invention is fully set forth in the following specification.

10 The object of our invention is to produce a spark with substantially the same current form that exists in the secondary circuit of a high tension magneto, a current of great pressure and volume.

15 As well understood by those skilled in the art it is necessary to quickly demagnetize the core of a spark coil to produce a current of great value in the secondary circuit for ignition purposes. In the usual spark coil 20 it is impossible to produce a spark of great value for the reason that the magnetic lines decrease in density slowly, decreasing more slowly as the magnetic flux lowers from the maximum density. This results in the current in the secondary circuit weakening or 25 dying before the core of the coil is completely demagnetized. To produce a spark from a spark coil that is equivalent to a high tension magneto spark, we have arranged a 30 coil and means of reversing the polarity within its core which causes a rapid demagnetizing effect with practically the same principle involved as in a high tension magneto, without the use of permanent magnets, 35 rotating armatures, or inductors. In our coil the polarity of the core is reversed which is the quickest way to cause a sudden collapse of the magnetic lines. This action causes a current of great value to continue 40 to flow in the secondary circuit as long as the magnetic lines are decreasing. By the reversing action produced in the magnetic lines, the slow rate of demagnetization is avoided by the rapid reversal produced.

45 Our invention overcomes the disadvantage found in the usual spark coil, as we do not rely on the magnetic lines decreasing slowly as explained above. Moreover in our coil the rapid change in the lines of force continue for a longer duration of time.

50 Devices of different forms may be used in the system containing our invention and the parts may be connected in different ways. To illustrate practical applications of the 55 invention we have selected a system that

contains the invention and shall describe it hereinafter.

Figure 1 illustrates diagrammatically the system. Fig. 2 indicates schematically the operations of the system.

Referring to the system in Fig. 1, 1 is a closed magnetic circuit type transformer. It is provided with a primary coil 2 and a secondary coil 13 on one side and an exciting coil 3 on the opposite side. Coils 2 and 3 are so wound that when current passes through them at the same time, magnetic lines are produced in the two sides of transformer which oppose each other with like poles at 16 and 17.

The circuits of coils 2 and 3 are completed by switch 4 and circuit breakers 6 and 7. The circuit breakers are operated by cams 8 and 9 which are connected to distributor 10.

The cams 8 and 9 and the rotating element 11 of the distributor are driven by the crank shaft of the engine and the parts are adjusted so as to cause manipulation of the parts of the system at the proper predetermined times to ignite explosive mixtures of the cylinders of the engine by the production of sparks at the terminals of spark plugs 12. The secondary coil 13 is connected to the rotating element 11 of the distributor and is thus connected to the spark plugs 12 in succession as the rotating element 11 makes contact sequentially with the fixed contacts 21, in the manner well known in the art. The character of the spark producer in the spark plugs 12 depends upon, as is well known, the character of the current produced in the secondary coil 13 which in turn is dependent upon the changes of the magnetic flux, and, particularly, the rapidity of change of the magnetic flux within the coil 13.

The return of the circuits of the parts of the system is through the ground, that is, through the body of the engine or the frame of the automobile. A suitable condenser is connected to the contact 14 which is shown at 22. A condenser may also be connected to contact 15 in the same manner as the condenser 22 although it is not necessary.

Figure 2 indicates the closed and open periods of the circuits through the exciter coil 3 and the primary coil 2 and illustrates diagrammatically the operation of the system.

Assuming switch 4 is closed and cam 8

has allowed circuit breaker 6 to close the primary circuit 2 at position indicated in chart in Fig. 2, the transformer 1 will be quickly built up to its maximum density, especially in winding 2, because substantially all of the magnetic lines travel completely around the transformer core in one direction and do not have to pass through any air resistance. Thirteen degrees later in the rotation of travel of the cams 8 and 9 as indicated in Fig. 2, cam 9 allows circuit breaker 7 to close exciter coil 3. The magnetic lines that were set up in winding 3 by the winding 2 are now choked back, although the magnetic lines in winding 2 still remain at a high density, because winding 2 was closed in advance to winding 3 and the magnetic lines set up by winding 2 strongly oppose the lines set up by winding 3, causing a slow building up within the core of winding 3. At this point the magnetic lines in 2 and 3 oppose each other causing the lines of force to pass through the air between the poles 16 and 17. Although windings 2 and 3 are opposing each other, winding 2 dominates because it was built up to its maximum before the circuit in winding 3 was closed, and also because winding 2 is now a closed circuit coil. Approximately 30 fifty-one degrees later as illustrated in Fig. 2, cam 8 opens circuit breaker 6 at position marked "Spark." Winding 2 no longer opposes winding 3 and the magnetic lines set up by winding 3 increase its lines of force 35 passing completely around the transformer and reversing the polarity of the core in winding 2 which causes a rapid collapse of the magnetic lines that were set up and maintained by winding 2, inducing a current 40 in the secondary winding 13 of great volume and pressure which is directed to a spark plug 12 by the distributor 10. Thirteen degrees later, cam 9 opens the circuit of the exciter coil 3. By the time this circuit opens, the 45 lines of force that were set up by winding 2 have been completely forced to zero and have started to build up in the opposite direction by exciter coil 3. Consequently the magnetic lines are still changing in density 50 when the circuit breaker 7 is opened which prevents spark formation at contact 15. It is essential that circuit breaker 7 does not remain closed long enough after circuit breaker 6 has opened, to build up the core 55 within the winding 2, to its maximum density, for if the circuit breaker 7 was opened at the time the flux was at its maximum there would be excessive sparking at contact 15. However, the arrangements and 60 adjustments of circuit breakers 6 and 7 and cams 8 and 9 may be varied considerably from Figs. 1 and 2 and still get the proper results. The degrees of opening and closure of the circuits indicated in Fig. 2 and Fig. 4 65 have been used only for purposes of illustra-

tion and consequently may be varied within the purview of the novelty of our invention.

We claim:

1. In a spark coil having a core of magnetic material, exciting and primary coils for producing opposing magnetic fluxes in the core, a secondary coil surrounding the primary coil, means for opening and closing the primary coil and exciting coil, the said means operating to open the primary coil in advance of the opening of the exciting coil. 70

2. In a spark coil having a core of magnetic material, exciting and primary coils for producing opposing magnetic fluxes in the core, a secondary coil surrounding the primary coil, means for opening and closing the primary coil and exciting coil, the said means operating to open the primary coil in advance of the opening of the exciting coil, the exciting coil being opened during the 85 open period of the primary coil.

3. In a spark coil having a core of magnetic material, exciting and primary coils for producing opposing magnetic fluxes in the core, a secondary coil surrounding the primary coil, means for opening and closing the primary coil and exciting coil, the said means operating to open the primary coil in advance of the opening of the exciting coil, the exciting coil being opened during 90 the open period of the primary coil, and the primary coil being closed while the exciting coil is open. 95

4. In a spark coil having a core of magnetic material, exciting and primary coils for producing opposing magnetic fluxes in the core, a secondary coil surrounding the primary coil, means for opening and closing the primary coil and exciting coil, the said means operating to open the primary coil in 100 advance of the opening of the exciting coil, the exciting coil being opened during the open period of the primary coil, the exciting coil being subsequently closed. 105

5. In an ignition spark coil, a core of magnetic material, a pair of exciting coils located on different portions of the said core, a source of direct current and a pair of circuit closers for connecting the exciting coils with the source of direct current and wound 110 and connected to produce opposing magnetic fluxes in different portions of the said core, a secondary coil located in inductive relation to one of the said exciting coils, means for operating the circuit closers to 115 close the circuit of one of the exciting coils to establish a magnetic flux in one direction in the magnetic core and subsequently closing the circuit of the other exciting coil to produce a magnetic flux in opposite directions in the magnetic core and subsequently disconnecting the exciting coil first connected to quickly deenergize the portion of the core on which the coil thus disconnected 120 is located and then subsequently establish- 130

ing magnetic flux in one direction within the said core and in a direction opposite to that in the portion of the core on which the disconnected exciting coil is located and subsequently deenergizing the said core.

6. In an ignition system, a source of direct current, a spark coil having a core of magnetic material and energizing coil and a primary coil located on different portions of the said core, a secondary coil in direct inductive relationship to the primary coil, a circuit closer for connecting the primary coil to the source of direct current to produce magnetic lines in one direction within the core, a circuit closer for connecting the energizing coil with the said source to produce opposing magnetic lines of force in the core and means for disconnecting the primary coil from the said source while the opposing fields exist.

7. In a spark coil having a core of magnetic material, a source of current, ex-

citing and primary coils for producing magnetic fluxes in opposite directions in the core, a secondary coil surrounding the primary coil, circuit breakers for controlling the circuits of the primary coil and exciting coil to sequentially open and close the circuits of the said coils to establish a magnetic flux in one direction by connecting one coil with the source of current and then setting up an opposing flux by connecting the other coil with the circuit when the change of flux produced by the first coil has become nil, and then disconnecting the first coil to permit the flux established by the second coil to pass through the portion of the core on which the secondary coil is located.

In testimony whereof we have hereunto signed our names to this specification.

LUTHER EARL SEVISON.
MARION MALLORY.
